UNITED STATES PATENT OFFICE.

WALTER R. LANGFORD, OF COALINGA, CALIFORNIA.

PIPE-WRENCH.

1,310,995.

Specification of Letters Patent. Patented July 22, 1919.

Application filed December 27, 1918. Serial No. 268,531.

To all whom it may concern:

Be it known that I, WALTER R. LANGFORD, a citizen of the United States, residing at Coalinga, in the county of Fresno and State 5 of California, have invented certain new and useful Improvements in Pipe-Wrenches; and I do declare the following to be a full, clear, and exact description of the invention, such as will enable others skilled in the art to 10 which it appertains to make and use the same.

My invention has for its object to provide an extremely simple and inexpensive, yet a highly efficient and reliable wrench for pipes 15 and other cylindrical parts, the arrangement being such as to positively prevent the wrench from dropping out of place after it has once been applied.

With the foregoing in view, the invention 20 resides in the novel features of construction and unique association of parts to be herein-after fully described and claimed.

Figure 1 of the accompanying drawings is 25 a side elevation of the wrench showing the same in operative position upon a pipe.

Fig. 2 is a side elevation partly in section showing the jaws released from the pipe.

Fig. 3 is a transverse section on the plane indicated by the line 3—3 of Fig. 1.

30 In the drawing above briefly described, the numeral 1 designates a preferably straight oscillatory handle having in its front end a diagonal cam slot 2 which is preferably located at one side of the longitudinal center of the handle as shown. Pivoted at 3 to the handle 1, in rear of the slot 2, is the rearwardly offset end of a semi-circular jaw 5, a shoulder 6 being formed at the juncture of the body portion of the jaw with 35 its offset end.

A second semi-circular jaw 7 is provided with a rearwardly offset rear end 8 which is pivoted at 9 to the handle 1 in rear of the pivot 3, the rear ends of both jaws being 45 preferably bifurcated at 10 to straddle the handle. The jaw 7 is provided with any suitable number of teeth 11 for non-slipping engagement with the pipe or other object indicated at 12.

50 To permit easy application of the tool to the work and removal therefrom, yet to retain the jaws 5 and 7 in such relation as to extend properly around such work, the front ends of said jaws are detachably connected 55 by a suitable spring pressed latch 12 preferably housed within recesses 13.

Positioned in front of the offset end 4 of jaw 5, is a curved pipe engaging shoe 14 having in its rear side a recess 15 into which the slotted front end of the handle 1 extends, 60 a pin 16 being passed across said recess and through the slot to pivotally connect the shoe and handle and to project said shoe into engagement with the pipe when the handle 1 is moved in one direction (see Fig. 1) and 65 to withdraw said shoe from contact with the pipe when the handle is shifted in the opposite direction as seen in Fig. 2. When this movement of the handle takes place, the shoe abuts the shoulder 6 and is thus limited in its 70 movement transverse of the handle, with the result that the cam slot 2 and pin 6 come into play to withdraw said shoe from the work as in Fig. 2.

From the foregoing, it will be seen that 75 the wrench is simple, inexpensive, highly efficient, and durable; and since probably the best results are obtained from the details set forth, they are preferably used, but within the scope of the invention as claimed, numerous minor changes may well be made.

I claim:

A pipe wrench comprising an oscillatory handle having in its front end a transverse diagonal slot, a curved jaw having its rear end offset rearwardly from the arc of said jaw and pivoted to said handle in rear of said diagonal slot, a second curved jaw opposed to said first named jaw and having its rear end offset rearwardly from the arc 90 of the jaw and pivoted to said handle in rear of the pivot of said first named jaw, means for detachably connecting the front ends of said jaws, a curved pipe engaging shoe in front of said offset end of the first named 95 jaw and having a recess into which the slotted front end of the handle projects, and a pin extending across said recess and through said slot, said pin and slot coacting to force said shoe against the pipe when the handle is moved in a direction to contract said jaws and serving to withdraw said shoe when the handle is moved in the opposite direction, said first named jaw having a shoulder at the point of offset of its rear end to limit 100 the movement of said shoe transversely of the handle when the latter is moved to release the jaws.

In testimony whereof I have hereunto set my hand.

WALTER R. LANGFORD.
